UNITED STATES PATENT OFFICE.

PHILIP SCHRAG, OF NEW YORK, ASSIGNOR TO EBERHARD FABER, OF PORT RICHMOND, N. Y.

LEAD AND CRAYON HOLDER.

SPECIFICATION forming part of Letters Patent No. 251,646, dated December 27, 1881.

Application filed October 11, 1881. (No model.)

To all whom it may concern:

Be it known that I, PHILIP SCHRAG, a citizen of the United States, residing at New York, in the county and State of New York, have invented new and useful Improvements in Lead and Crayon Holders, of which the following is a specification.

This invention relates to improvements in that class of lead or crayon holders which are provided with pivoted jaws acted on by springs to cause them to grasp and hold the lead or crayon, the said jaws being operated on by a conical slide moved from the exterior of the holder for releasing the lead or crayon.

The objects of my invention are to simplify the construction of such lead or crayon holders, to reduce the cost of manufacturing the same, and to utilize the inherent elasticity of the springs themselves for grasping and holding the lead or crayon. These objects I attain by the construction and arrangement of parts illustrated in the accompanying drawings, in which—

Figure 1 represents a longitudinal central section. Fig. 2 is a similar section at a right angle to Fig. 1.

Similar letters indicate corresponding parts.

The letter A designates the tubular stock or handle, which in this example is made of wood and provided with a metallic ferrule, A', at the lower end, terminating in a contracted nose or point.

B indicates the lead-containing tube, which is secured within the stock or handle in a fixed or stationary position, extends through the handle A, and terminates within the lower or outer end of its ferrule.

C are the spring closing jaws, having their free ends or points arranged to grasp the lead below the lower end of the lead-containing tube B, where the lead protrudes from such tube, and said springs are entirely inclosed within the ferrule, to avoid projections at the end of the holder. These jaws C are curved or bowed intermediate of their ends, as at C', to impinge against the inner surface of the ferrule A', es-

pecially when the jaws are opened or expanded, so that the bending of the jaws at the upper end is avoided, such bending having a tendency to wear or break the jaws at that place.

E designates the slide, constituting a means for opening the spring-jaws C. This slide consists of a tube fitted on the lower part of the lead-containing tube B, above the acting points of the spring-jaws C, its lower part or end being preferably tapered to correspond to the shape of the jaws at that place. When it is desired to open the spring-jaws C this tubular slide E is pushed down or outward, thus expanding the jaws, and when the slide is released it is automatically returned to an upper position by the action of the jaws, while the latter close to grasp the lead and hold it in place by their inherent elasticity.

F designates the finger-piece, serving to operate the jaw-opening slide E. In the present example this finger-piece F is made in the form of a button, having its shank fitted into a slot, g, in the ferrule A' of the handle, and secured to the slide in an appropriate manner, the slot forming a guide for the button in its movements.

What I claim as new, and desire to secure by Letters Patent, is—

The combination, with the stock or handle A and the attached ferrule A', having a slot, g, of the springs C C, having the curved or bowed portions C', intermediate of their ends which rest against the ferrule, and the slide E, located between the curved or bowed portions of the springs and their free ends, and having an attached finger-piece, by which it is operated, substantially as described.

In testimony whereof I have hereunto set my hand and seal in the presence of two subscribing witnesses.

PHILIP SCHRAG. [L. S.]
